UNITED STATES PATENT OFFICE.

ARNOLD KIENAST, OF LEIPZIG, GERMANY.

TURBINE.

1,022,683.

Specification of Letters Patent.

Patented Apr. 9, 1912.

Application filed September 26, 1910. Serial No. 583,739.

To all whom it may concern:

Be it known that I, ARNOLD KIENAST, citizen of Switzerland, residing at Leipzig, Germany, have invented certain new and 5 useful Improvements in Turbines, of which the following is a specification.

My invention relates to turbines for absorbing or supplying power and may be applied to turbines of the axial or tangential 10 type.

My invention relates more particularly to turbines so constructed that the impelling fluid, whether air, steam, water, or the equivalent passes through the same turbine- 15 wheel from one side to the other more than once.

My invention has for its object to provide a turbine with multi-stage impact and a number of rows of blade sections for every 20 wheel.

My invention has for its object to provide a type of turbine with a multi-stage impact and acting upon an increasing number of rows of blade sections on the successive ad- 25 mission of the power medium.

Referring to the drawings, Figure 1 represents a central section through the plane of the turbine, a segment only of the turbine being shown; Fig. 2 represents a diagrammatic elevation showing the sectional areas at the two ends of the first conduit or circulation passage; Fig. 3 is a section-view taken from above of a developed section along the line 3—3 of Fig. 1; and Figs. 4 30 and 5 are views showing the application of my invention to a tangential turbine engine.

In the turbines shown which comprise a casing A and a relatively movable element 40 B, the individual blades of which the moving element is composed are provided on their convex sides with transverse ribs C, D, E, F bearing against the adjacent blades. In this way the set of blades is divided into 45 three concentric rows of blade sections, with passages G, H, J. For the purposes of the present invention, it is immaterial as to how many sets of blades are formed in this manner and what their construction may 50 be. In place of the individual blades which are provided with ribs, the blades and ribs could be made integral with one another.

The passage of the impelling or working fluid through one set of blades is illus- 55 trated in Fig. 3. The working fluid enters the wheel at L for the first time and passes

through the same and out at M through the first conduit which it leaves at N to pass through the wheel for the second time. At O it flows into the second conduit, and at 60 P it enters the wheel for the third time, whence it leaves at Q. This operation can be repeated as many times as desired. The conduits which are successively traversed by the steam in thus passing through the turbine more than once are alternately arranged on opposite sides of the blade sections. Now according to the present invention the circulation and return flow of the working fluid takes place in such a manner 70 that upon each successive admission of driving fluid an increasing number of rows of blade sections is acted on. The arrangement is such that the radial height of the nozzle L is equal to that of the blade sec- 75 tions G, so that during the first impact the driving medium passes between L and M only through the passages G.

The dotted lines in Figs. 1 and 2 indicate the manner in which the conduit or 80 circulation passage overlaps only the outer row of blade sections at M whence it expands radially to the height or level of the blade sections G, H, thus conveying the working fluid from N to the outer and next 85 following group of blade sections. In this manner a constantly increasing number of rows of blade sections are operated upon. For axial admission the conduits need only vary in their radial dimensions and in- 90 versely in wheels with radial admission the dimensions of the conduits need vary only in axial direction.

Figs. 4 and 5 show the application of my 95 invention to a tangential turbine as distinguished from an axial turbine. In this type of construction the blades are separated by ribs running at right angles to the axis instead of parallel thereto and the conduits instead of becoming deeper radi- 100 ally for each successive conduit, now retain the same radial depth but become wider axially.

My invention may be used with turbines provided with any desired number of blades 105 and said blades may be of any desired size, whether large or small, without losing the advantages of said invention.

While I have described my invention as adapted to a turbine used as a source of 110 power it may also be applied to a turbine driven by power for the purpose of blow-

ing or compressing air or other fluids, or as a pump in various applications, without departing from the spirit of the invention.

I claim:

5. 1. In a single wheel turbine provided with a plurality of rows of blade sections, means comprising conduits alternately arranged on opposite sides of said blade sections for passing steam through said turbine more than once, said conduits being shaped to supply steam to an increased number of rows at each passage.
15. 2. In a turbine having blades provided with ribs between the blades so as to form a plurality of rows of blade sections, means comprising conduits alternately arranged on opposite sides of said blade sections adapted to pass steam through said turbine more than once and to supply steam to an increased number of rows at each passage, said conduits widening in a direction parallel with the blades and normal to said ribs.

3. In a turbine having blades divided by ribs into a plurality of radially arranged blade sections, means comprising conduits for passing steam through said turbine more than once, said conduits widening continuously in a radial direction.

4. In a single wheel turbine, in combination, a casing, a relatively movable element comprising a plurality of rows of blade sections, and a plurality of conduits fixed to said casing and alternately arranged on opposite sides of said relatively movable element for passing steam through said element more than once, said conduits being shaped to supply steam to an increased number of rows at each passage.

In testimony whereof I have hereunto set my hand in the presence of two subscribing witnesses.

ARNOLD KIENAST.
